DESIGN FOR A WHISTLE

Joseph R. Neill, Waterbury, Conn., assignor to
The Watertown Manufacturing Company,
Watertown, Conn., a corporation of Connecticut

Application May 11, 1935, Serial No. 56,779

Term of patent 14 years

To all whom it may concern:

Be it known that I, Joseph R. Neill, a citizen of the United States and residing at Waterbury, in the county of New Haven and State of Connecticut, have invented a new, original, and ornamental Design for Whistles, of which the following is a specification, reference being had to the accompanying drawing, forming part thereof.

Fig. 1 is a top perspective view of a whistle, showing my new design; and

Fig. 2 is a bottom perspective view thereof.

I claim:

The ornamental design for a whistle as shown.

In testimony whereof, I have affixed my signature to this specification.

JOSEPH R. NEILL.
